JOHN P. SIMMONS, OF SCHOOLCRAFT, MICHIGAN.

Letters Patent No. 88,089, dated March 23, 1869; antedated March 18, 1869.

IMPROVED WASHING-MACHINE.

The Schedule referred to in these Letters Patent and making part of the same.

To whom it may concern:

Be it known that I, JOHN P. SIMMONS, of Schoolcraft, in the county of Kalamazoo, and State of Michigan, have invented a new and useful Improvement in Combined Water-Heater and Washing-Machine; and I do declare that the following is a true and accurate description thereof, reference being had to the accompanying drawings, and to the letters of reference marked thereon, and being a part of this specification, in which—

Figure 1 is a perspective view, and

Figure 2 is a plan view of the apparatus, with the movable frame removed to show the heater and flue.

The nature of my invention consists in a movable frame placed within the body of the washing-machine, and having a perforated bottom, which frame can be lowered into or raised out of the water by suitable means, so that the clothes which lie in the frame can be subjected to the action of a wringer attached to the machine when frame E is raised.

To accomplish this purpose, I construct a proper frame, A, in which I place a tank, B, in the lower part of which is secured the water-tight heater and flue C, terminating in a pipe, D, for carrying away the smoke.

By making a fire in the stove C, the surrounding water in the tank is quickly brought to the boiling-point, effecting a great saving in boiling the fabrics in a separate vessel, and in handling them.

E is a movable frame, provided with a perforated bottom, F, and rollers G, the whole fitting easily into the tank B, and secured therein by a wedge, I.

H are standards, carrying guide-rollers, and erected on one end of the movable frame E.

J is a guide under the opposite end of the tank, provided with a pin, K, serving as a fulcrum for the slotted lever L, which actuates the reciprocating rod M, to which is secured the rub-board N.

The rod M is guided, in its reciprocating action, by its free end passing between the rollers in the standards H.

In washing with this apparatus, there should be sufficient water in the tank to cover the rollers G; and when the fabrics are cleansed, by withdrawing the wedge I, and raising the movable frame E above the water, which is done by throwing down the cams O, provided for that purpose, as shown in fig. 1, the water may be wrung or squeezed out of them, by subjecting them to the action of the rub-board N and rollers G.

What I claim as my invention, and desire to secure by Letters Patent, is—

1. The movable-frame E, wedge I, cams O, standards H, reciprocating rod M, lever L, guide J, and pin K, substantially as herein described and for the purposes specified.

2. The combination and arrangement of the above-named parts with the frame A, tank B, perforated plates F, rollers G, and rub-board N, when constructed, arranged, and operating substantially as herein described and for the purposes specified.

JOHN P. SIMMONS.
